US00D993972S

(12) **United States Design Patent** (10) Patent No.: **US D993,972 S**
Aponte et al. (45) Date of Patent: **** Aug. 1, 2023**

(54) **DISPLAY SCREEN OR PORTION THEREOF WITH GRAPHICAL USER INTERFACE**(71) Applicant: **Lutron Technology Company LLC**, Coopersburg, PA (US)(72) Inventors: **Nayda Aponte**, Northampton, PA (US); **Karelys Alfonzo**, Coopersburg, PA (US); **Advait Tinaikar**, Bethlehem, PA (US); **Brad Michael Kreschollek**, Bethlehem, PA (US); **Edward Wunsch**, Quakertown, PA (US); **Somesh Rahul**, Breinigsville, PA (US); **Sanjeev Kumar**, Harleysville, PA (US)(73) Assignee: **Lutron Technology Company LLC**, Coopersburg, PA (US)(**) Term: **15 Years**(21) Appl. No.: **29/817,959**(22) Filed: **Dec. 6, 2021****Related U.S. Application Data**

(63) Continuation of application No. 29/767,277, filed on Jan. 21, 2021, now Pat. No. Des. 940,160, which is a continuation of application No. 29/704,241, filed on Sep. 3, 2019, now Pat. No. Des. 909,402.

(51) **LOC (14) Cl.** ..... **14-04**(52) **U.S. Cl.**USPC ..... **D14/485**(58) **Field of Classification Search**USPC **D14/485-495**

Primary Examiner — Daniel J Domino(74) *Attorney, Agent, or Firm* — Saidman DesignLaw Group, LLC(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.
